UNITED STATES PATENT OFFICE.

LOT F. BURKE, OF SCHENECTADY, NEW YORK.

MOTOR-CYCLE.

1,269,379.

Specification of Letters Patent. Patented June 11, 1918.

Application filed July 2, 1917. Serial No. 178,140.

To all whom it may concern:

Be it known that I, Lot F. BURKE, a citizen of the United States, residing at Schenectady, county of Schenectady, and 5 State of New York, have invented certain new and useful Improvements in Motor-Cycles, of which the following is a specification.

Reference may be had to the accompanying drawings, and the reference characters marked thereon, which form a part of this specification. Similar characters refer to similar parts in the several figures therein.

This invention relates to shiftable seat-10 mechanism for a motor-cycle having two seats; and the principal object of the invention is to provide for arrangement of the seats at will, either side by side as twin seats, or one in rear of the other as tandem seats.

20 Other objects will appear in connection with the following description.

Figure 1 of the drawings is a view in side elevation of part of a motor-cycle provided with my improved shiftable seats.

25 Fig. 2 is a top plan view of the same with the seats arranged as twin seats.

Fig. 3 is a similar view with the seats arranged as tandem seats.

30 Fig. 4 is a vertical cross section taken on the broken line 4—4 in Fig. 1, showing the yoke whereby the rear end of the spring seat-mount is supported from the frame of the motor-cycle.

Fig. 5 is a vertical cross section taken on 35 the broken line 5—5 in Fig. 3.

Referring to the drawings wherein the invention is shown in preferred form, 1 is the frame of a motor-cycle, and 2 is a seat-mount in the form of a spring-leaf or strip, connected at its front end at 3 with the frame of the machine, and having its rear end supported in a bearing, 4, formed in a yoke, 5, the legs, 6, of the yoke being secured at 7 to the frame of the machine on opposite 40 sides of the wheel, 8.

The legs, 6, of the yoke may contain cushioning-springs, 9, if desired.

A channeled bracket, 10, is slidably mounted upon the spring-leaf, 2; and upon 50 this bracket are pivotally mounted a pair of seat-supporting bars, 11 and 12, with their respective pivotal connections, 13 and 14, arranged longitudinally of the bracket, and passing through intermediate portions of 55 the respective bars.

A seat, 15, is mounted upon the neighbor-

ing ends of said bars by means of pivotal connections, 16 and 17, which are arranged longitudinally of said seat.

A similar seat, 18, is mounted upon the 60 other ends of said bars by means of pivotal connections, 19 and 20, which are arranged longitudinally of said seat, 18.

The seat-supporting bars, 11 and 12, are offset to permit them to be swung upon the 65 respective pivotal connections, 13 and 14, to extend either transversely of the seat-mount, 2 and bracket, 10, as shown in Fig. 2, or longitudinally thereof as shown in Fig. 3, in either of which positions both seats face 70 forward.

The seat-mount, 2, bracket, 10, and seat-supporting bars, 11 and 12, are embraced between a pair of clamp-plates, 21 and 22, adapted to be drawn toward one another by 75 a pair of screw-bolts, 23, arranged on opposite sides of said seat-mount and bracket, whereby said bracket can be fixedly secured to the seat-mount, 2, and the seat-supporting bars, 11 and 12, can be secured in fixed relation to said seat-mount and bracket in either the twin-seat position shown in Fig. 2, or the tandem-seat position shown in Fig. 3.

80 The clamping-plate, 21, is preferably a 85 handle-base-plate from which is erected a handle, 24; and the plate, 21, is preferably provided with two sets of apertures for the bolts, 23, whereby it can be used as a clamp-plate with the handle, 24, extending longitudinally of the machine between the seats when arranged in twin-position as in Fig. 2, or transversely in front of the rear seat when the seats are arranged in tandem-position as shown in Fig. 3.

90 In shifting the seats from the position shown in Fig. 2 to that shown in Fig. 3, the bolts, 23, are removed, the seat-supporting bars, 11 and 12, are swung from their transverse position to their longitudinal position 95 with respect to the seat-mount, 2, and bracket, 10, and the bracket, 10, is slid rearward along the seat-mount, 2, until the seats in tandem-position are properly located upon the seat-mount. The seat-supporting 100 bars and bracket are then secured in fixed position upon the seat-mount, 2, by the clamping plates, 21 and 22, and bolts, 23.

105 In shifting the seats from the tandem-position shown in Fig. 3 to the twin-position shown in Fig. 2, the bolts, 23, are removed, the seat-supporting bars swung to transverse

position, and the bracket, 10, is slid forward along the seat-mount, 2, until the twin-seats are properly located, and the parts are then clamped in position as before.

5 If the clamping-plate, 21, is provided with the handle, 24, said clamp-plate is rotatively adjusted to cause the handle to extend longitudinally of the machine in the twin-position, and transversely of the machine in 10 the tandem-position of the seats.

What I claim as new and desire to secure by Letters Patent is—

1. The combination with a vehicle; of a seat-mount extending longitudinally of the 15 vehicle; a pair of seats; seat-supporting means shiftable to extend either longitudinally or transversely of said vehicle and said seat-mount, and supporting both seats in either of said positions with their longitudinal axes extending longitudinally of 20 said seat-mount and vehicle.

2. In a device of the class described and in combination, a seat-mount; a bracket shiftable longitudinally upon said seat- 25 mount; a pair of seat-supporting bars pivotally mounted intermediately of their ends upon said bracket; a pair of seats; pivotal connections between one of said seats and the respective neighboring ends of said bars, 30 and between the other of said seats and the respective other ends of said bars; and means for clamping said bracket and said bars upon said seat-mount with the bars extending either transversely or longitudinally 35 thereof.

3. The combination with a vehicle; of a support; a pair of seat-supporting bars pivotally mounted intermediately of their ends upon said support; a pair of seats; pivotal 40 connections between one of said seats and the respective neighboring ends of said bars, and between the other of said seats and the respective other ends of said bars; and detachable means for securing said bars in 45 fixed position upon said support with the bars extending either transversely or longitudinally of the vehicle, said pivotal connections being so located that said seats are supported in either position of said bars 50 with the longitudinal axes of the seats extending longitudinally of the vehicle.

4. In a device of the class described and in combination, a support; a pair of seat-supporting bars; pivotal connections between 55 said support and intermediate portions of the respective bars, said pivotal connections being arranged longitudinally of the support; pivotal connections arranged longitudinally of the respective seats between one of said seats and the respective

neighboring ends of said bars, and between the other of said seats and the respective other ends of said bars, said bars being offset to permit them to extend either transversely or longitudinally of said support; and detachable means for securing said bars fixedly in either of said positions upon said support. 65

5. In a device of the class described and in combination, a seat-mount; a bracket shiftable longitudinally upon said seat-mount; a pair of seat-supporting bars; a pair of seats; pivotal connections arranged longitudinally of said bracket between said bracket and the respective seat-supporting 75 bars; pivotal connections arranged longitudinally of the respective seats between one of said seats and the respective neighboring ends of said bars, and between the other of said seats and the respective other ends 80 of said bars, said bars being offset to permit them to extend either transversely or longitudinally of said support; and detachable means for fixedly securing said bracket in selected position upon said mount, and 85 said bars in either of said positions upon said bracket.

6. In a device of the class described and in combination, a support; a pair of seats; seat-supporting means shiftable to extend 90 either longitudinally or transversely of said support; detachable means for fixedly securing said seat-supporting means in either of said positions upon said support; and a handle mounted upon said support between 95 said seats.

7. In a device of the class described and in combination, a support; a pair of seat-supporting bars pivotally mounted intermediately of their ends upon said support; a 100 pair of seats; pivotal connections between one of said seats and the respective neighboring ends of said bars, and between the other of said seats and the respective other ends of said bars; detachable means for securing said bars in fixed position upon said support with the bars extending either transversely or longitudinally thereof, said means including a handle base-plate; and 105 a handle erected from said base-plate. 110

8. A seat attachment for motor-cycles having two seats, and means for supporting said two seats either side by side or one in front of the other, with their longitudinal axes in either position extending longitudinally of the motor-cycle. 115

In testimony whereof, I have hereunto set my hand this 29th day of June, 1917.

LOT F. BURKE.
